UNITED STATES PATENT OFFICE

HARRY SCHREIBMAN, OF BROOKLYN, NEW YORK, ASSIGNOR TO CAPITAL LIGHTING FIXTURE COMPANY, INC., A CORPORATION OF NEW YORK

DESIGN FOR A LIGHTING FIXTURE

Application filed July 21, 1931. Serial No. 40,616. Term of patent 3½ years.

To all whom it may concern:

Be it known that I, HARRY SCHREIBMAN, a citizen of the United States of America, and a resident of Brooklyn, in the county of Kings and State of New York, have invented a new, original, and ornamental Design for a Lighting Fixture, of which the following is a specification, reference being had to the accompanying drawings, forming a part hereof.

In the drawings:

Fig. 1 is a side elevational view of the lighting fixture; and

Fig. 2 is an inverted plan view of the same.

The fixture is characterized by an opaque bowl-like body A which carries a plurality of translucent shades B for concealing light sources and a centrally located clock C adapted to be viewed from underneath.

I claim:

The ornamental design for a lighting fixture substantially as shown and described.

HARRY SCHREIBMAN.
